UNITED STATES PATENT OFFICE.

JAMES B. HOWARD, OF INDIANAPOLIS, INDIANA.

DESIGN FOR A HEATING-STOVE.

40,764.

Specification for Design.

Patented July 12, 1910.

Application filed May 4, 1910. Serial No. 559,420. Term of patent 14 years.

To all whom it may concern:

Be it known that I, JAMES B. HOWARD, a citizen of the United States, residing at Indianapolis, in the county of Marion and State of Indiana, have invented a new, original, and ornamental Design for Heating-Stoves, of which the following is a specification, reference being had to the accompanying drawings, forming part thereof.

In said drawings—Figure 1 is a view in front elevation. Fig. 2 is a view in side ele-

vation of one of the sides of the stove, one side of the stove being a symmetrical duplicate of the other; and Fig. 3 is an elevation of the rear of the stove.

I claim:

The ornamental design for a heating stove, as shown.

JAMES B. HOWARD.
